UNITED STATES PATENT OFFICE.

GEORGE CLAUSING, OF PORTSMOUTH, OHIO, ASSIGNOR TO THE VULCAN BOX TOE PROCESS COMPANY, OF PORTSMOUTH, OHIO, A CORPORATION OF OHIO.

SHOE-LAST.

1,128,586.

Specification of Letters Patent. Patented Feb. 16, 1915.

Application filed February 26, 1914. Serial No. 821,168.

To all whom it may concern:

Be it known that I, GEORGE CLAUSING, a citizen of the United States, residing at Portsmouth, Scioto county, State of Ohio, have invented a certain new and useful Improvement in Shoe-Lasts, of which the following is a full, clear, and exact description, such as will enable others skilled in the art to which it appertains to make and use the same, reference being had to the accompanying drawings, forming part of this specification, in which—

Figure 1 is a longitudinal sectional view through my improved last. Fig. 2 is a cross 15 sectional view on line 2—2 of Fig. 1.

This invention relates to a new and useful improvement in shoe lasts, the object being to construct a last which is simple, cheap, and one which can be "broken" and removed from the shoe. The last is provided with a hinge and one of the hinged members co-operates with a spring in such a manner that the parts of the last are normally held in operative position, the hinge member and 20 spring being so constructed that the heel and toe members of the last are locked against accidental displacement.

In the drawings 1 indicates the heel member of the last and 2 the toe member, these 30 members being suitably shaped and provided with openings at their contiguous faces.

3 indicates a tube inserted in an opening in the toe member and held therein by 35 means of a cross pin 4. The outer end of this tube is slotted to receive the pintle-end of a hinge member 5, fitted in the opening of the heel member of the last and held in position by a cross pin 6.

40 7 is the pintle which passes through registered openings in the tube and hinged member 5.

The hinged member 5 has an extension 5* at its outer end which extension co-operates 45 with a ball or plunger 8 pressed thereagainst by a spring 9 arranged in an opening in the toe member of the last. This extension has its outer face slightly concave so that when the parts are in normal position, as shown in Fig. 1, the spring pressed ball rests in a socket and forms an effective lock to prevent accidental displacement of the hinged parts of the last. The locked

position of the parts requires exertion of some considerable pressure in swinging the 55 heel portion of the last upwardly in removing it from a shoe, but of course this is the intended operation and when the last is removed from the shoe, the parts of the last will immediately resume their normal positions relative to each other. Obviously, however, it can be arranged to hold the last in its broken position.

In speaking of the extension 5*, the shape of whose working face which co-operates 65 with the spring-pressed ball as constituting a "lock" for the hinged members of the last, it is of course understood that this so-called "lock" merely prevents accidental displacement of the last members by requiring a 70 greater initial pressure to swing said members on the hinged pintle than is necessary to continue the movement after the last members are initially "broken."

What I claim is:

75 1. A shoe last composed of two members hinged together, a hinge connecting said members consisting of two elements secured to the last members and pivotally connected together, one of said elements having a recessed extension and a spring pressed member co-operating with said recessed extension whereby the pivotally connected members of the last have a constant pressure exerted thereon to hold them in their normal or 80 closed position, said spring-pressed member being located above the pintle of the hinged elements.

2. In a shoe last the combination with heel and toe members, of a tube secured in one of 90 said members and provided with a slot in its outer end, a pintle member secured in the other last-member and having its outer end arranged in the slot of the tube and provided with a projection, the pintle passing through 95 the slotted end of the tube and said hinge member, and a spring pressed element located above the tube and co-operating with said extension.

In testimony whereof I hereunto affix my 100 signature in the presence of two witnesses, this 9th day of February, 1914.

GEORGE CLAUSING.
